(57) **CLAIM**

The ornamental design for a charging base for a wireless camera, as shown and described.

DESCRIPTION

FIG. 1 is a top, front, right side perspective view of a charging base for a wireless camera, showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a top, front, right side perspective view of the charging base for a wireless camera of FIG. 1, shown in a condition of use.

Broken lines in the drawings depict portions of the charging base for a wireless camera that form no part of the claimed design. In FIG. 8, the broken lines showing a wireless camera depict environmental subject matter only, and form no part of the claimed design.
